UNITED STATES PATENT OFFICE.

ABRAHAM W. LOZIER, OF NEW YORK, N. Y.

STYLOGRAPHIC FOUNTAIN-PEN.

SPECIFICATION forming part of Letters Patent No. 233,106, dated October 12, 1880.

Application filed August 7, 1880. (No model.)

To all whom it may concern:

Be it known that I, ABRAHAM W. LOZIER, of New York, in the county and State of New York, have invented a new and Improved 5 Stylographic Pen, of which the following is a specification.

Figure 1 is a side view of my improved stylographic pen, and Fig. 2 is a central longitudinal section thereof.

- 10 This invention relates to a very simple and efficient and easily-regulated construction of stylographic pen; and it consists in extending the stem which carries the writing-spindle through the entire length of the apparatus, in 15 cushioning it near the upper end, in combining it with a peculiar filler and air-tube, in providing it below said tube with a valve for 20 closing the latter, and in other details of improvement hereinafter more fully pointed out.
- 25 In the accompanying drawings, the letter A represents the shell of the pen, which may be made of glass, hard rubber, or any other suitable material. To the lower end of this shell is secured the ink-discharge nipple B, through 30 which the writing-spindle C protrudes. Said spindle C is a fine-wire coil at its upper portion, as shown at *a*, and fitted by its coil part upon a stem or rod, D, which is grooved, roughened, or notched at the lower part to hold the coil portion properly in place. The roughening of the lower part of stem D is not illustrated.

35 By this construction I am enabled to secure the writing-spindle upon the stem by merely slipping its coil portion off, thereby allowing its easy replacement when worn, and enabling me to supply each pen with a series of said spindles, either one of which the owner may use. The spindle C can be lengthened by stretching the coil.

- 40 The stem D is screw-threaded, except at its ends, and a short distance below its upper end a collar, *b*, is screwed to it. Above this collar is a spring, *d*, which bears against the under side of the turned-in flange *e* of the filling-tube 45 E. This filling-tube, which also serves as an air-tube to discharge the ink in writing, has a screw-threaded outer portion, *f*, that is screwed into the upper end of the shell A, so that thus the shell A is closed on top by the filling-tube, 50 which tube, moreover, guides the stem D, holds it centrally, and allows it a slight up-

ward play, giving elasticity to the act of writing. The inwardly-turned flange *e* is centrally perforated to allow the stem D to freely move up and down therein. Above the flange *e* is 55 fitted a rubber cushion, *g*, which is held in place above by a plate, *h*, into which it is secured by being sprung into an undercut seat. The plate *h* embraces the stem D, and is itself held fast by a suitable clasp, *i*, that engages 60 in one of two cross grooves or notches, *l* 2, in stem D. The plate *h* prevents the stem from dropping downward, whereas the upward play of the stem is regulated by the collar *b* and spring *d*. The filler and air-tube E is surrounded by a series of slightly-projecting 65 rings, *j*. Below the filler-tube the stem D carries a valve, *k*.

When the filler-tube is unscrewed from the shell A at *f* it draws the stem D and writing-spindle C out of the shell A, allowing the latter to be readily repaired or replaced. If the stem is to be detached from the filler-tube, the plate *h* is unfastened, so as to allow the stem to be drawn downward out of said tube. The 70 filler-tube is used for filling by dipping its lower portion into an ink-reservoir, and then carrying the supply it contains to the shell, holding the upper opening of the filler-tube 75 closed with the finger until the tube E is over 80 the shell, when the finger is removed and the ink can flow into the shell. The rings *j* retain some of the ink, into which the tube is dipped, and show thereby the depth to which the tube was inserted, which otherwise could 85 not be conveniently ascertained, and by this means the user is enabled to regulate the supply of ink with great nicety.

Should the ink-bottle from which the supply is to be obtained be too deep and the ink 90 too low therein to use the filler, the ink can be drawn by gentle suction of the lips directly through the aperture in the lower end of A into A, and by inserting filler E into A to the highest ring thereon. The depth of the ink 95 taken into tube A can be ascertained by the wetting of sides of B, and can be allowed, if in excess, to escape to the proper amount—as, e. g., so many drops for ink found between successive spaces between the rings.

100 When the pen is put together, as shown in Fig. 2, and supplied with ink, it can be used

in writing like any other stylographic pen. If the writer desires to put the pen into his pocket, and to prevent the ink from flowing into the tube E, and thence penetrating into the pocket, he first pulls the stem D upward so as to close the valve k against the lower end of the filling-tube and catch the spring-clasp i, attached to plate h, into the lower groove, 1, of the rod D. This also retracts the writing end of C into A and preserves it from breaking. The pen is then inverted, causing the ink in the shell to flow into the space which surrounds the filling-tube, and to remain there while inverted (in which position it should be in the pocket) without having an opportunity to flow into the filling-tube.

Should the pen choke in writing, as often happens in stylographic pens, the style-rod D is seized at the upper projecting end and 20 worked back and forth till obstruction is removed.

I claim—

1. A stylographic pen composed of a shell, A, filler and air-tube E, and stem D, the stem carrying the writing-spindle and being attached to the tube E, all arranged so that an air-space surrounds the stem within and along the tube E, substantially as described.

2. The stem D, carrying the writing-spindle and provided with a projecting collar, b, in combination with the spring d, which bears upon said collar, and with the inwardly-turned flange e on the inserted filling-tube E above said spring, substantially as described.

3. The combination of the cushion g with 35 the plate h, clasp i, stem D, and filler and air-tube E, substantially as shown and described.

4. The combination of the shell A, filler and air-tube E, movable stem D, writing-spindle C, and valve k, for operation substantially as 40 described.

5. The filler and air-tube E, constructed with the embracing and projecting rings j, substantially as and for the purpose specified.

6. The combination of the stem D, carrying 45 the spindle C, and having notches 1 and 2 above the tube A, with the clasp i, also above said tube A, and with the air-tube E, said clasp serving to properly hold the spindle C either in the lower working position or elevated, substantially as herein shown and described.

ABRAHAM W. LOZIER.
